UNITED STATES PATENT OFFICE

OTTO SCHWARTZ, OF DETROIT, MICHIGAN

RADIATOR COVER

Application filed November 10, 1930. Serial No. 494,522.

The present invention relates to radiator shields or covers, or so-called "enclosures".

An object of this invention is a shield of the character shown in the patent to Otto Schwartz, No. 1,519,011, granted December 9, 1924, the present shield having a sweep sheet which is provided on its under surface with a filter medium designed to trap a large portion of the dust which passes from behind the radiator and out from under the sweep sheet. It is intended to so dispose the filtering medium, which may be steel wool saturated with an odorless oily substance, that is removable as a unit from the sweep sheet. In this manner, replacement of the filtering medium, when it becomes clogged with dust, may be readily effected.

A further object is a novel form of joint or connection between the horizontal sweep sheet and the vertical back plate, so that replacement of the filtering medium may be effected without difficulty.

A still further object is a radiator shield wherein a dust proof joint or connection between the vertical back plate and the horizontal sweep sheet is provided and wherein a filtering medium is disposed in the path of the circulating air.

Still further objects will readily occur to those skilled in the art upon reference to the following description and the accompanying drawings in which

Fig. 1 shows in outline a radiator provided with the shield of the novel design.

Fig. 2 is an enlarged detail sectional view of a portion of the sweep sheet.

Fig. 3 is a similar view of a portion of the back plate and sweep sheet illustrating the joint or connection between them.

Fig. 4 is a bottom plan view of a portion of the sweep sheet as if looking upwardly towards the portion shown in Fig. 2.

Referring to the drawings, it will be seen that there is provided on the floor 10 and adjacent the vertical wall 12 a radiator 14 which may be of any conventional design. Disposed in back of the radiator and leading from a point close to the floor to a point above the top of the radiator is a back plate 16 to which is detachably connected the

sweep sheet 18 of the invention. End flanges shown in dotted lines at 20 are connected to the back plate, and secured to these end flanges are mounting or fastening means of the character disclosed in the patent above mentioned, although it will be understood that other mounting means may be used if desired.

The joint or connection between the back plate 16 and the sweep sheet 18 is illustrated best in Fig. 3 and is formed as follows: The edge of the back plate 16 is bent in the form of a reversed S to provide a groove or pocket 24 in which may be slid an edge of the sweep sheet 18. The pocket 24 is made of such a size as to receive the edge of the sweep sheet rather closely so that a substantially close fit between them is provided, thus preventing the gathering of dust in the connection.

It will be observed that the connection is substantially air-tight and dust-proof and being so constructed forms an important part of the present invention.

Secured to the under surface of the sweep sheet as illustrated in Figs. 2 and 4, are a plurality of clips 30 which secure a plate 32 to the bottom of the sheet.

The plate 32 is indent on three of its edges to provide grooves 34 to receive the outwardly bent flanges 36 of the wire cage 38, as illustrated in Fig. 2. One edge, preferably the end edge of the sheet 32 is left unbent so that the cage 38 may be slid outwardly from between the indent edges of this member. Further, the member 32 itself is detachable from the sweep sheet since it can be slid out from between the clips and the bottom of the sheet.

Disposed within the wire cage 38 is a mass of mineral wool 40 saturated with an odorless oily substance rendering the steel wool dust-collecting in its nature. The forward edge of the sweep sheet is bent in the form of a J—as illustrated at 42 to provide a pocket in which dust may be collected.

Disposed above the horizontal sweep sheet is a cover 46 and between the latter and the top surface of the sheet is a layer of heat insulating material such as asbestos at 48.

It will be observed that air which circu-

lates around and thru the radiator in the direction of the arrows and which carries with it a considerable quantity of dust gathered from the floor and walls, is conducted thru and against the mass of steel wool 40. A certain proportion of the dust carried by the air is collected on the wool, there to remain until the wool is replaced by a fresh quantity. Some of the dust that is not collected by the wool gathers in the pocket 42 of the sweep sheet, as will be understood clearly, from where it can be removed.

It will also be seen that there has been provided a radiator shield which traps a considerable quantity of the circulating dust although not interfering appreciably with the circulation of air around the radiator.

Further, it will be seen that the dust collecting devices are readily replaceable by fresh ones so that the maintenance of the efficiency of the device will be a comparatively simple matter.

Now having described the invention and the preferred embodiment thereof, it is to be understood that the said invention is to be limited, not to the specific details herein set forth, but only by the scope of the claim which follows.

What I claim is:

1. In a radiator shield, a back wall, and a sweep sheet detachably connected thereto by means of a substantially air-tight joint, said sweep sheet comprising a horizontal plate having filtering material on its under surface, and a vertical J-shaped flange projecting downwardly and inwardly from the front edge of the sweep sheet to serve as an auxiliary dust trap, the joint between the back and the sweep sheet including a pocket-forming bend on the back sheet into which an edge of the sweep sheet is adapted to fit, the filtering material being disposed in a flat wire cage removably supported on the under surface of the sweep sheet, the material being removable from the cage so as to be replaced if desired the shield having a removable cover fitted over the sweep sheet, and the upper edge of the back plate, and concealing the J shaped flange of the sweep sheet.

OTTO SCHWARTZ.
